CLAIM

The ornamental design for a side brush for cleaning robot, as shown and described.

DESCRIPTION

FIG. 1 is a front view of a first embodiment of a side brush for cleaning robot, showing the new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front-top-right perspective view thereof;

FIG. 8 is a rear-bottom-left perspective view thereof;

FIG. 9 is a front view of a second embodiment of a side brush for cleaning robot, showing the new design;

FIG. 10 is a rear view thereof;

FIG. 11 is a left side view thereof;

FIG. 12 is a right side view thereof;

(Continued)

FIG. 13 is a top view thereof;
FIG. 14 is a bottom view thereof;
FIG. 15 is a front-top-right perspective view thereof; and,
FIG. 16 is a rear-bottom-left perspective view thereof.
